CLAIM

The ornamental design for a baby monitor base, as shown and described.

DESCRIPTION

FIG. 1 is a perspective view of the baby monitor base holding an unclaimed baby monitor and showing our new ornamental design.

FIG. 2 is another perspective view thereof.

FIG. 3 is a back elevation view thereof.

FIG. 4 is a front elevation view thereof.

FIG. 5 is a top, plan view thereof.

FIG. 6 is a bottom plan view thereof.

FIG. 7 is a right elevational view thereof; and,

FIG. 8 is a left elevational view thereof.

Objects shown in broken lines are shown for environmental purposes only and form no part of the claimed design.
